PUMPING APPARATUS

Robert Griffin De La Mater, Parkersburg, W. Va., assignor to The Parkersburg Rig & Reel Company, Parkersburg, W. Va., a corporation of West Virginia

Application May 12, 1936, Serial No. 79,376

21 Claims. (Cl. 74—41)

This invention relates to pumping apparatus, and more particularly to a pumping unit for use in connection with oil wells.

An important object of the invention is to provide a novel apparatus of the character referred to which greatly facilitates the servicing of an oil well.

A further object is to provide a novel type of walking beam for a pumping unit, which is adapted to be swung to an inoperative position to facilitate the servicing of the well.

A further object is to provide a novel type of walking beam which normally operates as a unitary construction and which is provided with hinge means intermediate its ends to permit the hinging of the pumping end of the beam with respect to the pivot support of the beam to permit the pumping end to be swung to a position substantially out of alignment with the pump rods.

20 A further object is to provide an apparatus of the character referred to having means associated with the hinged walking beam for supporting the inner end of the beam when the outer end is swung to the inoperative position referred to.

25 A further object is to provide a headache post having its upper end arranged slightly below the lower face of the walking beam when the latter is in its lower limit of normal travel, and wherein the headache post is adapted to support the inner end of the hinged beam referred to when the pumping end of the beam is swung upwardly to inoperative position.

30 A further object is to provide a hinged walking beam of the character referred to wherein the hinged sections of the beam are adapted to be readily restored to their normal positions after the pumping end of the beam has been swung to its upper inoperative position.

35 A further object is to provide a two part walking beam of the character referred to having simple means for securing the sections of the beam in operative position and wherein the securing means in the normal operation of the beam is not subject to destructive stresses or strains of any kind.

40 A further object is to provide a walking beam of the character referred to in combination with counter-weighted driving means therefor, wherein the counter-weight means employed is adapted to support the free end of the hinged beam in its upper inoperative position without the use of any separately operative holding means.

45 Other objects and advantages of the invention

will become apparent during the course of the following description.

In the drawings I have shown one embodiment of the invention. In this showing—

5 Figure 1 is a side elevation of a pumping unit embodying the invention.

Figure 2 is a fragmentary elevation of one end of the apparatus showing the walking beam and associated parts.

10 Figure 3 is a similar view of the other end of the apparatus.

Figure 4 is a perspective view of the walking beam.

15 Figure 5 is a fragmentary vertical sectional view through the central portion of the walking beam, taken substantially on line 5—5 of Figure 4, and.

Figure 6 is a detail vertical sectional view 20 through the walking beam taken on line 6—6 of Figure 5.

Referring to the drawings, the numeral 10 designates a concrete or similar foundation for the pumping apparatus, and a pair of channel section base rails 11 are bolted or otherwise secured to the foundation as at 12. The apparatus 25 is adapted to be driven by means of a prime mover 13 which may be of any desired type, such as an electric motor or internal combustion engine. The prime mover is adapted to deliver power in any suitable manner, as by means of a belt 14, to 30 a pulley 15. Suitable speed reducing gearing (not shown) is arranged within a housing 16 and this gearing transmits power from the pulley 15 to a crank shaft 17.

Opposite ends of the crank shaft 17 are provided with cranks 18 to one end of each of which is connected a wrist pin 19. A substantially U-shaped pitman is adapted to be driven by the wrist pins 19 and this pitman includes depending arms 20 and a cross head 21. Each crank arm 18 40 is provided at the end opposite the wrist pin 19 with a plurality of counter-weights 22, the function of which is well known in connection with pumping units of this character. The various elements of the apparatus described including the 45 source of power and the transmission means between such source of power and the pitman, form no part of the present invention, except in the combination to be referred to later.

50 A Samson post indicated as a whole by the numeral 23 is arranged adjacent one end of the apparatus and comprises vertical parallel post members 24 each of which carries a bearing 25 adjacent its upper end to receive the ends of a pivot shaft 26. Forwardly of the Samson post 55

a headache post 27 is arranged, and this post also preferably includes parallel post members connected at their upper ends by an angle member 28. An angular brace member 29 is provided for the Samson post, and a plurality of horizontal brace members 30 are arranged against and secured to the outer faces of the members 24, 27 and 29, as shown in Figure 1. These various elements are preferably welded together to provide an integral assembly of parts.

The apparatus includes a novel type of walking beam indicated as a whole by the numeral 31. The walking beam is preferably of I-beam section, as indicated in Figures 2 and 3, and comprises a pair of sections 32 and 33 arranged in end to end relation. The end to end relation of the beam sections is clearly shown in Figure 5, and it will be noted that a plate 34 is welded against opposite edges of the flanges of the beam section 32. These plates extend above and below the walking beam and substantially over-lap the joint therebetween. The inner end of the beam section 33 is provided adjacent opposite sides thereof with ears 35 projecting upwardly from the upper base of such beam section. A relatively heavy pivot shaft 36 projects through the ears 35 and through the plates 34. A pair of angles 37 and 38 are welded against the lower bases of the respective beam sections 32 and 33. These channels are provided with depending bases 39 and 40 having their adjacent faces normally contacting in the plane of the joint between the beam sections 32 and 33, and are normally held together by a single bolt 41.

It will become apparent that the beam sections 32 and 33 normally operate as a unitary walking beam, and the lower limit of movement of the bottom of the beam during the pumping operation is indicated by the dot and dash line 42 in Figure 1. It is noted that this line is slightly above the upper face of the angle 28 at the upper end of the headache post 27, and during the servicing of the well the beam sections are adapted to assume the preferred positions shown in dotted lines and designated by the numeral 43. If desired, the beam may be swung upwardly as a unit to the dotted line position shown in Figure 4 and designated by the numeral 44, in which case extraneous supporting means for the beam must be employed.

One end of the walking beam is provided with a bearing member 45 carried by the beam section 32 and receiving the pivot shaft 26. It will be apparent that the particular pivot supporting means for the beam is of no importance in connection with the present invention, since any suitable means for the same purpose may be employed. The cross member 21 of the pitman carries suitable bearing portions 46 to receive a pivot shaft 47 extending through the bearings 48 mounted on the upper face of the walking beam. The working end of the beam is provided with the usual rod hanger 49, as shown in Figure 1, and any suitable type of rod hanger and its connection with the walking beam may be employed.

The operation of the apparatus is as follows:

The prime mover 13 drives the crank shaft 17 through the belt 14 and the reducing gearing 70 thus rotating the cranks 18. The wrist pins 19 obviously rotate about the axis of the shaft 17 and transmit a rocking motion to the walking beam through which the pumping action is transmitted to the pump rods. It will be noted that power is delivered to the walking beam at a point ad-

jaacent the rod hanger instead of delivering the power to an extended end of the walking beam on the opposite side of the pivot support thereof from the rod hanger. This fact is of importance for several reasons. So far as the present invention is concerned, it will be noted that the driving arrangement referred to permits the use of a relatively light walking beam. Due to the weight of the pump rods and the weight transmitted to the free end of the walking beam during the pumping action, the Samson post is retained under tension at all times instead of under compression as is true of conventional pump units.

Since an upward force is always exerted at the pivoted end of the walking beam, it will be apparent that during the operation of the apparatus, regardless of the position of the parts, a substantial force is exerted at the joint of the walking beam to tend to maintain the beam sections in operative position with respect to each other. In other words, the top of the beam is maintained under tension while a compression force exists between the adjacent ends of the beam sections at the bottom thereof under all normal working conditions, and accordingly there is no strain placed on the locking bolt 41. As a matter of fact, the use of this bolt is not essential in view of the presence of the forces tending to retain the joint in closed position, but the use of the bolt is preferred to prevent vibration from tending to open and close the joint between the beam sections.

As previously stated, the lower limit of movement of the bottom of the walking beam is indicated by the dot and dash line 42, which lies slightly above the top of the headache post. Accordingly the walking beam is adapted to oscillate about its pivot without interference from the headache post. When it is desired to service the well, the wrist pins 19 will be turned to their lower positions to swing the walking beam to its lower limit of movement, whereupon the pump rods may be disconnected. Under ordinary conditions, the weight of the pump rods and the force of the pumping action tend to move the free end of the walking beam downwardly thus tending to cause the beam to pivot about the axis of the pitman shaft 47 and urge the pivoted end of the beam upwardly. As stated, it is these forces which tend to maintain the pivot point in closed position.

After the pump rods have been disconnected there is no longer any force present tending to hold the beam joint closed, and the operator then may remove the bolt 41, whereupon the joint between the beam sections will open sufficiently to lower the beam section 32 into contact with the headache post 28 to be supported thereby. The crank shaft 17 is then rotated through approximately a half revolution to move the wrist pins 19 upwardly and swing the counter-weights 22 to their lowermost position shown in dotted lines in Figure 1. With the beam section 32 supported on a headache post, the turning of the crank shaft in the manner referred to swings the pitman to its dotted line position and likewise swings the beam section 33 to the inoperative position indicated by the numeral 43 in Figure 1. Under such conditions the free end of the beam obviously will be moved laterally away from its normal path of movement to a sufficient extent to permit the well to be readily serviced. In this connection it will be noted that no fastening means is necessary for holding the beam section 33 in its inoperative position since the counter-

weights will be at their lower position and serve by gravity alone to support the beam section 33 in the position referred to. If desired, the walking beam may be swung upwardly as a unit to the dotted line position shown in Figure 4, in which case the derrick line will be employed for elevating the beam. This requires of course, that the wrist pin bearings at the lower ends of the pitman arms be disconnected from the wrist pins 19.

Assuming that the beam section 33 has been swung to the position indicated by the numeral 43 and it is desired to restore the normal operation of the apparatus after servicing has been completed, the counter-weights 22 will again be swung to their upper positions and the wrist pins 19 to their lower positions, and this operation will leave only a slight gap between the ends of the beam sections. The further steps for restoring the normal condition of the beam may be carried out in several ways. For example, the pump rods may be again connected in the usual manner, and the weight thus placed on the free end of the beam will move the jointed portion of the beam upwardly to close the joint, whereupon the bolt 41 may be applied. As an alternative method of closing the joint between the beam sections, the derrick line may be attached to the hinged portion of the beam to pull such portions upwardly and thus close the joint to permit the insertion of the bolt. It will be apparent that the simplest method of closing the beam joint is merely to insert the bolt 41 and tighten it, thus drawing the angles 37 and 38 together. Upon the restoration of the beam sections to their normal condition and the hanging of the pump rods from the free end of the walking beam, the apparatus is again ready for operation. In connection with the removing and applying of the bolt 41, it will be noted that the rail members 30 act as ladder members to permit an operator to readily climb upwardly to a point in proximity to the beam joint, and at the same time the members 33 act as braces between the elements to which they are connected.

From the foregoing it will be apparent that the present apparatus greatly facilitates the servicing of a well by providing means whereby the free end of the walking beam may be readily swung laterally out of alignment with the well to provide access thereto. It also will be apparent that the relationship of the driving and working elements of the beam are such as to permit the use of a relatively light beam and to normally operate under all conditions to retain the joint in closed position and prevent the transmission of any strain to the locking bolt 41. The position of the headache post is such as to facilitate the supporting of the beam section 32 when the well is to be serviced, and the headache post will support the entire beam under all conditions in the event of any breakage of the parts. The counter-weights 22 operate to perform their normal functions in the operation of the pumping unit, and at the same time they provide means for holding the beam section in its upper inoperative position without the necessity for providing extraneous supporting means for the free end of the beam.

It is to be understood that the form of the invention herewith shown and described is to be taken as a preferred example of the same and that various changes in the shape, size and arrangement of parts may be resorted to without

departing from the spirit of the invention or the scope of the subjoined claims.

I claim:

1. A walking beam for pumping apparatus comprising a pair of beam sections arranged in end to end relation, and a horizontal hinge connecting the adjacent end portions of the beam to mount the beam sections for relative swinging movement in a vertical plane, and counterbalance means tending to swing one of said beam sections with relation to the other.

2. A walking beam for pumping apparatus comprising a pair of beam sections arranged in end to end relation, a horizontal hinge connecting the adjacent end portions of the beam to mount the beam sections for relative swinging movement in a vertical plane, and means for securing said beam sections against relative movement, and counterbalance means tending to swing one of said beam sections with relation to the other.

3. A walking beam for pumping apparatus formed of a pair of beam sections arranged in end to end contacting relation and forming a beam unit having pivoting, pumping and driving connections so related as to maintain the beam under compression at one edge and under tension at the opposite edge, and a hinge connecting said beam sections adjacent the tensioned edge of the beam, and counterbalance means tending to swing one of said beam sections in the direction of the compression edge of the beam unit.

4. A walking beam for pumping apparatus formed of a pair of beam sections arranged in end to end contacting relation and forming a beam unit having pivoting, pumping and driving connections so related as to maintain the beam under compression at one edge and under tension at the opposite edge, a hinge connecting said beam sections adjacent the tensioned edge of the beam, and means adjacent the compression edge of the beam for securing the adjacent end portions of the beam sections to each other, and counterbalance means tending to swing one of said beam sections in the direction of the compression edge of the beam unit.

5. A pumping apparatus comprising a walking beam formed of a pair of beam sections arranged in end to end contacting relation, a horizontal hinge connecting the adjacent end portions of the beam sections adjacent the top of the beam to mount the beam sections for relative swinging movement in a vertical plane, means pivotally supporting the free end of one of said beam sections to support the beam for oscillating movement in a vertical plane, and a stationary support arranged beneath the last named beam section slightly below the lower limit of the path of oscillation thereof.

6. A pumping apparatus comprising a walking beam formed of a pair of beam sections arranged in end to end contacting relation, a horizontal hinge connecting the adjacent end portions of the beam sections adjacent the top of the beam to mount the beam sections for relative swinging movement in a vertical plane, means pivotally supporting the free end of one of said beam sections to support the beam for oscillating movement in a vertical plane, a stationary support arranged beneath the last named beam section slightly below the lower limit of the path of oscillation thereof, and means adjacent the bottom of the beam for se-

curing the adjacent ends of the beam sections to each other.

7. A pumping apparatus comprising a walking beam formed of a pair of beam sections arranged in end to end contacting relation, a horizontal hinge connecting the adjacent end portions of the beam sections adjacent the top of the beam to mount the beam sections for relative swinging movement in a vertical plane, 10 means pivotally supporting the free end of one of said beam sections to support the beam for oscillating movement in a vertical plane, a pumping connection at the free end of the other beam section, driving means connected to said last named beam sections inwardly of the free end thereof, and a stationary support arranged beneath said first named beam section slightly below the lower limit of its path of oscillation.
8. A pumping apparatus comprising a walking 20 beam formed of a pair of beam sections arranged in end to end contacting relation, a horizontal hinge connecting the adjacent end portions of the beam sections adjacent the top of the beam to mount the beam sections for relative swinging 25 movement in a vertical plane, means pivotally supporting the free end of one of said beam sections to support the beam for oscillating movement in a vertical plane, a pumping connection at the free end of the other beam section, driving 30 means connected to said last named beam section inwardly of the free end thereof, a stationary support arranged beneath said first named beam section slightly below the lower limit of its path of oscillation, and means adjacent the bottom of 35 the beam for securing the adjacent ends of said beam sections to each other.

9. A pumping apparatus comprising a walking beam formed of a pair of sections having adjacent ends connected for relative swinging movement about a horizontal axis whereby one beam 40 section is adapted to swing upwardly with respect to the other beam section, means for pivotally supporting the beam, a driving connection for the beam, a pumping connection at the free end of the first named beam section, and means 45 for supporting the first named beam section when it is swung upwardly with respect to said other beam section.

10. A pumping apparatus comprising a walking beam formed of a pair of sections having adjacent ends connected for relative swinging movement about a horizontal axis whereby one beam section is adapted to swing upwardly with respect to the other beam section, means for pivotally supporting the beam, a driving connection 50 for the beam, a pumping connection at the free end of the first named beam section, means for supporting said other beam section independently of said first named beam section, and means for supporting the first named beam section when it is swung upwardly with respect to said other beam section.

11. A pumping apparatus comprising a walking beam formed of a pair of sections having adjacent ends connected for relative swinging 65 movement about a horizontal axis whereby one beam section is adapted to swing upwardly with respect to the other beam section, means for pivotally supporting the beam, a driving connection for the beam, a pumping connection at the free end of the first named beam section, means for supporting said other beam section independently of said first named beam section, a drive shaft, a crank carried by said drive shaft, and operable through said driving connection 70

for oscillating the beam, and a counter-weight fixed with respect to said shaft and arranged substantially diametrically opposite said crank.

12. A pumping apparatus comprising beam sections arranged in end to end contacting relation and forming a beam unit having pivoting, pumping and driving connections so related as to maintain the beam under compression at one edge and under tension at the opposite edge, a hinge connecting said beam sections adjacent the tensioned edge of the beam to mount the sections for relative swinging movement in a vertical plane, counter-weight means for supporting out of alignment with the other beam section the beam section having said driving connection, and 15 stationary means for supporting said other beam section.

13. A pumping apparatus comprising a pair of beam sections arranged in end to end contacting relation, means adjacent the free end of one beam section for pivotally supporting the beam, a pumping connection at the free end of the other beam section, a driving connection for the last named beam section, a hinge connecting the adjacent ends of said beam sections adjacent the top of the beam to mount the last named beam section for upward swinging movement with respect to the first named beam section, stationary means for supporting said first named beam section independently of the other beam section, 30 and counter-weight means for supporting the second named beam section when it is swung upwardly with respect to said first named beam section.

14. A pumping apparatus comprising a pair of beam sections arranged in end to end contacting relation, means adjacent the free end of one beam section for pivotally supporting the beam, a pumping connection at the free end of the other beam section, a driving connection for the last named beam section, a hinge connecting the adjacent ends of said beam sections adjacent the top of the beam to mount the last named beam section for upward swinging movement with respect to the first named beam section, stationary means for supporting said first named beam section independently of the other beam section, and counter-weight means connected to said driving connection for supporting the second named beam section when it is swung upwardly with respect to said first named beam section.

15. A pumping apparatus comprising a pair of beam sections arranged in end to end contacting relation, means adjacent the free end of one beam section for pivotally supporting the beam, a pumping connection at the free end of the other beam section, a driving connection for the last named beam section, a hinge connecting the adjacent ends of said beam section adjacent the bottom of the beam to mount the last named beam section for upward swinging movement with respect to the first named beam section, stationary means for supporting said first named beam section independently of the other beam section, a crank shaft operable through said driving connection for oscillating the beam, and a counter-weight carried by said crank shaft.

16. A pumping apparatus comprising a walking beam formed of a pair of beam sections arranged in end to end contacting relation, means adjacent the free end of one beam section for pivotally supporting the beam, a pumping connection at the free end of the other beam section, a driving connection for the last named beam section, a hinge connecting the adjacent ends 70

of said beam sections adjacent the top of the beam, and counterbalance means tending to lift said last named beam section.

17. A pumping apparatus comprising a walking beam formed of a pair of beam sections arranged in end to end contacting relation, means adjacent the free end of one beam section for pivotally supporting the beam, a pumping connection at the free end of the other beam section, a driving connection for the last named beam section, a hinge connecting the adjacent ends of said beam sections adjacent the top of the beam, means for securing the bottom portions of the adjacent ends of the beam sections to each other, and counterbalance means tending to lift said last named beam section.

18. A pumping apparatus comprising a walking beam formed of a pair of beam sections arranged in end to end contacting relation, means adjacent the free end of one beam section for pivotally supporting the beam, a pumping connection at the free end of the other beam section, a driving connection for the last named beam section, a hinge connecting the adjacent ends of said beam sections adjacent the top of the beam, and means for limiting downward movement of said first named beam section.

19. A pumping apparatus comprising a walking beam formed of a pair of beam sections arranged in end to end contacting relation, means adjacent the free end of one beam section for pivotally supporting the beam, a pumping connection at the free end of the other beam section, a driving connection for the last named beam section, a hinge connecting the adjacent ends of said beam sections adjacent the top of the beam, means for securing the bottom portions of the adjacent ends of the beam section to each other, counterbalance means tending to lift said last named beam section, and means for limiting downward movement of said first named beam section.

connecting the adjacent ends of said beam sections adjacent the top of the beam, means for securing the bottom portions of the adjacent ends of the beam sections to each other, and means for limiting downward movement of said first named beam section. 5

20. A pumping apparatus comprising a walking beam formed of a pair of beam sections arranged in end to end contacting relation, means adjacent the free end of one beam section for pivotally supporting the beam, a pumping connection at the free end of the other beam section, a driving connection for the last named beam section, a hinge connecting the adjacent ends of said beam sections adjacent the top of the beam, 15 counterbalance means tending to lift said last named beam section, and means for limiting downward movement of said first named beam section.

21. A pumping apparatus comprising a walking beam formed of a pair of beam sections arranged in end to end contacting relation, means adjacent the free end of one beam section for pivotally supporting the beam, a pumping connection at the free end of the other beam section, a driving 25 connection for the last named beam section, a hinge connecting the adjacent ends of said beam sections adjacent the top of the beam, means for securing the bottom portions of the adjacent ends of the beam section to each other, counterbalance 30 means tending to lift said last named beam section, and means for limiting downward movement of said first named beam section.

ROBERT GRIFFIN DE LA MATER.
